(57) CLAIM

I claim the ornamental design for a footwear upper portion, as shown and described.

DESCRIPTION

FIG. 1 is a perspective view, from the front end and right side, of a footwear upper portion, showing my new design; FIG. 2 is top view thereof;

FIG. 3 is a right side view thereof;

FIG. 4 is a left side view thereof;

FIG. 5 is a front end view thereof; and,

FIG. 6 is a rear end view thereof.
